UNITED STATES PATENT OFFICE.

E. L. PRATT, OF BOSTON, MASSACHUSETTS.

IMPROVED APPLE-PARER.

Specification forming part of Letters Patent No. 40,185, dated October 6, 1863.

To all whom it may concern:

Be it known that I, E. L. PRATT, of Boston, in the county of Suffolk and State of Massachusetts, have invented a new and useful Improvement in Apple-Paring Machines; and I do hereby declare that the following, taken in connection with the drawings which accompany and form part of this specification, is a description of my invention sufficient to enable those skilled in the art to practice it.

In apple-paring machines, as usually made, after the knife has operated over the surface of the apple and arrived at the farther end thereof, it is released and flies back to its original or normal position, to commence on the next apple. In thus flying back the knife or knife-head strikes against and jams the surface of the pared apple; and my improvement consists in so operating the rod or arm that carries the cutter-head and knife that the knife and cutter-head shall clear the surface of the apple as they spring back after paring the same.

The invention is shown in the accompanying drawings, Figure 1 of which represents a plan of an apple-paring machine having the improvement applied to it, and Fig. 2 a vertical cross-section taken on the line $x-x$ of Fig. 1.

The machine shown is made and operated to pare the apple as is usual with many or all of these machines in common use, and it will not be necessary, therefore, to particularly describe its construction or operation, which will readily be understood from inspection of the drawings.

The plate a , which actuates the knife-arm c , is applied to the end of the shaft b , and has an elongated slot, d , made in it, in which the arm c works in the usual manner, and as the knife is carried around the apple by this plate the spring i draws the arm toward the apple, and keeps the knife against its surface. The lower side of this slot has a depression, e , extending from it, as seen in Fig. 2, such depression being made of a size sufficient to receive the arm c . To one side of the frame-work A of the machine, and adjacent to the bearing f of the shaft b , I apply a cam-plate, g , having

an inclined cam-surface, h . On the opposite side of the shaft, and extending up from the frame A , and just in rear of the depression e of the slot d , as seen in Fig. 2, is a stop-plate, k . The operation of this depression e , cam h , and lifter-plate k on the arm c serves to carry said arm into the depression after the knife has pared the apple, to keep the arm in such depression while the knife is thrown back, and to release the arm from the depression and allow the spring i to draw it into its normal position, or in position to commence paring another apple.

The operation of the invention is as follows: As the apple is rotated on its fork l , and the knife begins to traverse around it by the co-operating rotation of the slotted plate a on its shaft b , the arm c is pressed outward into the slot by the enlargement of the apple. As the knife reaches or nearly reaches the opposite end of the axis of the apple, the arm c is brought into contact with the inclined cam-face h of the plate g , and as the shaft b continues to rotate the arm c is carried outward by the inclination of the cam, and is pressed against the upper surface of the slot d until it is pushed into the depression e , which is made narrow at its mouth or opening, so that as the arm slips therein, as seen by dotted lines in Fig. 2, it is held there by the retraction of the spring i . The knife has now been carried beyond or away from the surface of the apple, so that when the cogged sector on the shaft b is next released from the gear rotating it, as is usual in these machines, and the spring on the shaft carries the knife-arm and knife around the surface of the apple, the depression e retains the knife-arm and keeps the knife and cutter-head from contact with the apple. The arm keeps in the depression until it reaches the top of the stop-plate k , when it is held or stopped by said plate until the depression descends below it, when the arm is drawn by the spring down its slot d , and the knife is brought to its normal position.

In the use of apple-paring machines as now made much trouble is experienced from the cutter and cutter-head striking against the pared surface and jamming or detaching

portions thereof, which trouble my improvement will be found to wholly obviate, as the knife and cutter-head are kept entirely away from such surface after the paring operation is performed.

What I claim is—

Keeping the knife and cutter-head from the surface of the apple, after the same is pared,

in the manner and by the mechanism, substantially as described.

Executed this 12th day of September, A. D. 1863.

E. L. PRATT.

In presence of—

J. B. CROSBY,
FRANCIS GOULD.
